UNITED STATES PATENT OFFICE.

WILLIAM A. RINGLER, OF PHILADELPHIA, PENNSYLVANIA, ASSIGNOR TO GLOBE-WERNICKE COMPANY, OF CINCINNATI, OHIO, A CORPORATION OF OHIO.

VISIBLE-INDEX-CARD SYSTEM.

Application filed February 19, 1924. Serial No. 693,782.

My present invention comprehends a novel visible index card system, wherein the card-holders and their cards are constructed and connected together in a novel manner.

5 It further comprehends a novel construction of cards and card-holders and novel means for connecting the cards with respect to their holders so that the cards and card-holders are reversible as a unit of structure 10 without detaching the cards from their card-holders, and thus permit the recording of the desired matter on both sides of the cards without detaching them from their holders.

Other novel features of construction and 15 advantage will hereinafter more clearly appear in the detailed description and the appended claims.

For the purpose of illustrating the invention, I have shown the accompanying drawing 20 ing a typical embodiment of it, which, in practice, will give reliable and satisfactory results. It is however to be understood that this embodiment is typical only and that the various instrumentalities of which my 25 invention consists can be variously arranged and organized, and that the invention is not limited to the precise arrangement and organization of these instrumentalities as herein set forth.

30 Figure 1 is a plan view of a plurality of cards and card-holders of a visible index card system embodying my invention.

Figure 2 is a plan view of another embodiment of my invention.

35 Figure 3 is a section on line 3—3 of Figure 1.

Figure 4 is a plan view of another embodiment of the invention.

Figure 5 is a plan view of the card seen 40 in Figure 1.

Figure 6 is a plan view of another embodiment of my invention.

Figure 7 is a section on line 7—7 of Figure 1.

45 Figure 8 is a section on line 8—8 of Figure 2.

Figure 9 is a section on line 9—9 of Figure 6.

50 Figure 10 is a section on line 10—10 of Figure 4.

Similar numerals of reference indicate corresponding parts.

Referring to the drawings:—

Referring first to the embodiment seen in 55 Figures 1, 3 and 5, 1 designates cards and

2 card-holders of a visible index card system embodying my invention. The cards have extending transversely across them a weakened line 3 which divides the cards into a recording portion 4 and a holding portion 5, 60 which latter has spaced openings 6 arranged preferably in pairs. The card-holders 2 are each formed in the shape of a strip folded to a V-shape in cross section, each flange of which is preferably of the 65 same dimensions.

The card-holders in Figures 1, 3 and 7 are provided with the spaced openings 7, through which is passed a locking member 8 in the form of a wire or rod having relatively offset portions 9, as clearly illustrated in Figure 3. If it is desired to remove the card from its card-holder, the locking member 8 is withdrawn. The locking member 8 is withdrawn by deforming it 70 and removing it from the card holder and card, and this locking member is preferably made of an easily bendable wire.

In the embodiment seen in Figures 2 and 8, the card 10 is similar to that seen in Figure 5 except that the openings 6 may be omitted. The card 10 is inserted into a V-shaped card-holder 11 and secured therein by means of the clips 12. The clips 12 are in the form of U-shaped staples. 85

In the embodiment seen in Figures 4 and 10 the cards 10 are secured in the card-holders 11 by paper clips 14 of well-known construction having a prong 15 to penetrate the card-holder and card. These clips 90 14 as shown consist of U-shaped strips.

In the embodiment seen in Figures 6 and 9, the cards and card-holders are of the same construction as seen in Figure 4 except that the card-holders have openings 16 95 which register with openings 17 in the card 10 to receive the clips 18 similar to those seen in Figure 4, but instead of clipping over the card-holders, they pass through the registering openings 16 and 17 and the free 100 ends of the clips are pressed together as seen in Figure 9.

In all of the embodiments herein shown, the card-holders nest one within another to cause the cards to overlap to form visible 105 index portions 19. Due to the fact that the cardholders have their flanges of the same width, it will be apparent that any card and its card holder as a unit of structure can be reversed so that the reverse face of 110

the card is visible for recording purposes. When a card holder is reversed, its overlapping relationship with the juxtaposed card holder will be the same, and the fastening devices determine the visibility of the card and card holder.

The free ends of the card-holders extend beyond the cards which they carry, and are adapted to be slidably mounted in the conventional type of frame having opposite marginal edges inturned to form guide flanges between which and the body portion of the frame the free ends of the card-holders are guided.

15. The holding portion of a card is preferably of substantially the same width as the width of a fold of its card-holder, so that the weakened line or the line on which the card bends or is hinged is in close proximity to the marginal edge of a fold of the card-holder.

Having thus described my invention, what I claim as new and desire to secure by Letters Patent, is:

25. 1. In a visible card index system, the combination of card holders, cards, and fastening devices to secure the marginal portion of a card within its card holder, one card holder being adapted to nest within another card holder with the fastening devices limiting such nesting to determine the visibility of the cards, each card holder consisting of a folded strip with the folds of substantially the same width to provide for the reversibility of the card and card holder, and each card having a weakened line near the lower edge of its card holder to permit bending of the card in its original and in its reverse position.

40. 2. In a visible card index system, the combination of card holders, cards, and fastening devices to secure the marginal portion of a card within its card holder, one card holder being adapted to nest within another card holder with the fastening devices limiting such nesting to determine the visibility of the cards, each card holder consisting of a folded strip with the folds of substan-

tially the same width to provide for the reversibility of the card and card holder, and each card having a weakened line near the lower edge of its card holder to permit bending of the card in its original and in its reverse position and said fastening devices being removable to permit the removal of a card from its card holder.

3. In a visible card index system, the combination of card holders and cards having registering openings, and removable fastening devices to pass through said openings to secure the marginal portion of a card within its card holder, one card holder being adapted to nest within another card holder with the fastening devices limiting such nesting to determine the visibility of the cards, each card holder consisting of a folded strip with the folds of substantially the same width to provide for the reversibility of the card and card holder, and each card having a weakened line near the lower edge of its card holder to permit bending of the card in its original and in its reverse position.

4. In a visible card index system, the combination of card holders and cards having registering openings, and removable fastening devices to pass through said openings to secure the marginal portion of a card within its card holder, one card holder being adapted to nest within another card holder with the fastening devices limiting such nesting to determine the visibility of the cards, each card holder consisting of a folded strip with the folds of substantially the same width to provide for the reversibility of the card and card holder, and each card having a weakened line near the lower edge of its card holder to permit bending of the card in its original and in its reverse position, and said fastening devices consisting of longitudinally extending strips of material alternately offset in opposite direction to contact with opposite sides of their card holders.

WILLIAM A. RINGLER.
